Isadore Albert Lipman, Meriden, Conn., assignor to Ellmore Silver Co., Inc., Meriden, Conn., a corporation of Connecticut

Application August 4, 1953, Serial No. 26,263

Term of patent 14 years

(CL. D44—29)

To all whom it may concern:

Be it known that I, Isadore Albert Lipman, a citizen of the United States and residing at Meriden, in the county of New Haven and State of Connecticut, have invented a new, original, and ornamental Design for a Combined Bottle and Can Opener, of which the following is a specification, reference being had to the accompanying drawings, forming part thereof.

Fig. 1 is a top plan view of a combined bottle and can opener, showing my new design; Fig. 2 is a side elevational view thereof; while Figs. 3 and 4 are respectively sections taken along lines III and IV of Fig. 1.

I claim:

The ornamental design for a combined bottle and can opener, as shown.

ISADORE ALBERT LIPMAN.
